[57] CLAIM

The ornamental design for a tape storage rack, as
shown and described.

DESCRIPTION

FIG. 1 is a front perspective view of the tape storage
rack of the present invention oriented for placement on
a floor or table; and

FIG. 2 is a front elevational view of the tape storage
rack of FIG. 1, but oriented as in wall mounting.

The side of the rack not shown is like the side shown
while the rear surface and undisclosed end are plain
and unornamented.
